FIG - 2 -

FIG - 3 -

UNITED STATES PATENT OFFICE

SOLOMON SPECTOR, OF LA FAYETTE, INDIANA

INCINERATOR

Application filed July 19, 1927. Serial No. 206,912.

This invention relates to new and useful improvements in incinerators.

The device is intended for use by families in their yard in burning up rubbish, garbage, waste paper and the like and by its use will prevent fires to buildings now often caused by carelessness in destroying waste matter.

In the accompanying drawings:

10. Figure 1 is a vertical longitudinal sectional view, of an incinerator embodying my improvements.

Figure 2 is a horizontal section, taken on line 2—2 of Figure 1 and Figure 3 is a vertical transverse section, taken on line 3—3 of Figure 1.

Referring to the drawings for a more particular description of my invention, A designates the incinerator, as a whole, which is in 20 the form of a hollow rectangular oblong casing or receptacle, consisting of the side and end walls 1 and 2, respectively, top and bottom 3 and 4 and the supporting legs 4'.

The casing is re-inforced by an inner 25 skeleton frame composed of the vertical corner angle bars 5, the flat intermediate vertical side bars 6, the cross bars 7 extending between the corner bars 5, at the ends of the casing or receptacle, the intersecting longitudinal and cross bars 8 and 9 at the top and the intersecting longitudinal and cross bottom bars 10 and 11, respectively. The various bars aforesaid forming the skeleton frame are bolted or otherwise fastened together at their points of intersection or engagement. The top, bottom, side and end walls are also re-inforced by the wire fabric strips 12 and 13. The top 3 is made removable and may be taken off like the lid of a 40 box.

The top of the casing or receptacle is provided at one end with a suitable feed opening 14 through which the trash or other waste matter to be burned is introduced and this 45 opening may be closed by a suitable cover 15 preferably equipped with a hinged bail or handle 16. The top of the casing is provided at its opposite end with a removable chimney 17, as shown. One end of the casing is provided with a suitable draft opening 18 and

the bottom of the casing is provided with a centrally disposed rotating door 19 for emptying or dumping the ashes. This door is carried by one end of a horizontal shaft 20 suitably journaled in place and provided at 55 its outer end with a crank handle 21.

Having described my invention, what I claim as new and desire to secure by Letters Patent, is:

1. A device of the character specified, 60 comprising a hollow rectangular oblong casing consisting of an inner metal skeleton frame covered on the outside with re-inforced cement, a removable top for the casing, said top provided with a feed opening, a removable cover for said feed opening, a chimney at the opposite end of top and a manually operated revolving dumping grate for the bottom of the casing.

2. A device of the character specified, comprising a hollow rectangular oblong casing consisting of an inner metal skeleton frame covered on the outside with re-inforced cement, said skeleton frame comprising vertical corner bars, flat intermediate vertical side bars, cross bars extending between the corner bars at the ends of the casing and top and bottom intersecting longitudinal and cross bars.

In testimony whereof he affixes his signature.

SOLOMON SPECTOR.
